METHOD OF FORMING A SPARK PLUG

Edward B. Nowosielski, Bloomfield, N. J., assignor to Eclipse Aviation Corporation, a corporation of New Jersey

Application June 2, 1937, Serial No. 146,092

2 Claims. (Cl. 29—155.51)

This invention relates to spark plugs, and particularly to those intended for use under severe conditions as to heat development and current intensity, necessitating maximum efficiency in heat dissipation and in electrode construction. This application is composed of subject matter divided out of my applications Serial No. 16,832 filed April 17, 1935 now Patent No. 2,088,384; Serial No. 29,530 filed July 2, 1935 now Patent No. 2,081,500; and Serial No. 62,524 filed February 5, 1936.

Some of the objects are to provide improved electrodes including novel methods of constructing and assembling the electrodes, and of adjusting the spark gap; to provide improved heat deflecting means; and to provide other improvements and advantageous combinations the nature of which will appear.

These and other objects of the invention will become apparent from inspection of the following specification when read with reference to the accompanying drawings wherein is illustrated the preferred embodiment of the invention. It is to be expressly understood, however, the drawings are for the purpose of illustration only, and are not designed as a definition of the limits of the invention, reference being had to the appended claims for this purpose.

In the accompanying drawings forming part hereof:

Fig. 1 is a view in elevation of one embodiment of the invention;

Fig. 2 is a longitudinal sectional view of the plug shown in Fig. 1 but on an enlarged scale;

Fig. 3 is a bottom plan view of the plug;

Fig. 4 is a sectional view of the central electrode in course of formation;

Fig. 5 is a diagrammatic view showing an alternative shape for the electrodes 106 and 109 of Fig. 3;

Fig. 6 is a longitudinal sectional view of a different embodiment of the invention;

Fig. 7 is a bottom plan view of the plug shown in Fig. 6;

Fig. 8 is a longitudinal sectional view of the lower portion of a plug similar to that of Fig. 2 except for the type of grounded electrode construction; and

Figs. 9 to 13 inclusive, indicate the appearance of the element 66 of Fig. 8 as it passes through the successive stages in the process of forming it into its final condition.

For the purpose of a shielded aviation spark plug the metal body 10 of the plug is provided with a shield extension 11 which extends up-

ward considerably above the upper end of the spindle 12 to enclose the spindle and the electrical connection 62 between the spindle 12 and the conductor 66 which supplies the high-tension current. This extension 11 is preferably in one piece with the attaching nut 5, though such unity is not necessary.

Instead of completely closing the space between the shield extension 11 and spindle 12, I provide a cooling and ventilating chamber 13 in the form of an annular space between the shield extension 11 and a long thin cylindrical metallic sleeve 14 lined with a tube 15 formed of rolled mica constituting the wall of a second chamber which is bounded at its lower end by the upper surface of the compressible metal gland 17, and at its upper end by a novel heat deflecting and sealing assembly more fully described, as well as claimed, in my application No. 16,832 above identified. For a similar reason certain other elements are not discussed in detail herein; the detailed description herein being confined to those features which are more particularly the subject of this application. Among these is the central electrode 106 whose outer surface has an elliptical contour, as indicated best in Fig. 3, while the cooperating parallel walls 107 and 108 of the outer electrode 109 form a parallelogram as viewed in Fig. 3. In place of a true elliptical contour for the part 106 as shown in Fig. 3 the contour may be a combination of arcs and parallel edges as shown at 206 in Fig. 5. Either arrangement permits ready adjustment of the spark gap by producing relative angular motion between the parts 106 and 109 (or 206 and 209) about the common axis of said parts. This adjustment can be effected by inserting in the space between the two elements a gage of proper thickness to give the desired spark clearance and then applying said gage to the elements as a lever to cause one of said elements to turn sufficiently to produce the desired clearance therebetween. Electrode 109 is integrated with the recessed end 94 of the shell 36 by fusing or bonding it thereto through the instrumentality of a joining piece 111 of a soft metal similar to that of the sleeve 95 which bonds part 106 to spindle 12 in the manner hereinafter outlined in connection with the description of the central electrode assembly as shown in Figs. 2 and 4. Gland 17 of Fig. 2 has a tapered surface for registry with a correspondingly tapered seat 114 in the shell 36, to supplement the heat dissipating action of the soft metal rods 19, and the openings 40 also aid in such heat dissipation. Also in this embodiment

ment I provide an asbestos heat baffle 113, and a pedestal 117 of current conducting carbonium or stainless steel having low heat conductivity to further reduce the amount of heat entering contact spring 61 which maintains the electrode pin 62 in contact with the conductor 66. Cable spacer 77 is free to move upwardly beyond rim 118 of member 83, but only to the point of contact with the annular rim 119 on the swivel member 169. The said member 169 is internally threaded to receive a correspondingly threaded gland 121 of steel or similar material to firmly grip the inwardly turned end 122 of a metallic corrugated tube 123 which, by reason of the pressure exerted thereupon by the application of the nut 121, is pressed firmly upon the beveled annular seat 124 of a bonding member 125, constituting the means for providing a firm electrical bond between the shielding elements 123 and 169, the latter being in firm contact with the complementary shielding element 11 by reason of the pressure exerted thereupon by the act of tightening the coupling nut 71 threaded to the upper end of the shield extension 11. This nut 71 is shown at 70 (Figs. 1 and 2) as milled out horizontally and also vertically to increase the effectiveness of the hold. This milling provides flexibility which facilitates establishment of a locked connection by the exertion of inward pressure upon the open ends.

The metallic washer 39, described above, corresponds to the thrust washer 38 of my Patent No. 2,081,500; through this metallic washer pressure is applied to the gland 17 to insure a firm bond 35 or seal along the taper of the gland, thus preventing the escape of the confined cylinder gases, the pressure being applied as a result of threading the shield extension 11 into the shell 36, substantially as described in my said Patent No. 2,081,500. Also as described in said patent, this firm engagement between the parts 17 and 36 provides an effective path for the heat that flows outwardly through the pressure gland 17 and toward the radial openings in the shell 36.

45 The electrode cup 106 is initially of uniform bore, so that it may be slipped over the enlarged base of spindle 12 and its covering sleeve 95 (as indicated in Fig. 4) and then secured in position thereon by a pressure sufficient to change the cross-section of the upper end of said cup 106 to cause its contour to conform to that of the spindle base and sleeve 95, all said parts being fused into a unitary assembly by the process.

50 As shown in Figs. 6 and 7 the outer electrode 8 is made in one piece, electrically or otherwise welded, to the shell along the two cylindrical surfaces indicated at 5 and 6, between which surfaces there is a peripheral groove adapted to be filled by metallic ring 4 of a softer material such as copper having greater heat conductivity so as to facilitate the dissipation of excess heat which might otherwise develop into grounded electrode 8. It will also be noted that although the normal path across which the high tension current 55 will jump includes that portion of the electrode which is directly below the base of the central electrode 7, there is an auxiliary potential spark gap across to the inwardly extending circular ledge indicated at 3; but the primary purpose of this ledge 3 is to constitute a baffle to impede an entry into the interior of the plug of objectionable products of combustion.

To conform to standard practice, shell 11 will be made from suitable free-turning steel, while electrode 8 will be made from bendable metal having

good spark resistant qualities, as, for example, a nickel-manganese alloy.

Also as shown in Fig. 6, the insulator 20 is of ceramic material such as porcelain, positioned solidly within the shell by the action of threading parts 10 and 11 together. This action holds the insulator 20 against the shouldered portion 30 of the shell, a seal against escape or entry of fluid being effected at this point by the provision of the gasket 31 engaging the shoulder 30. Above this shoulder 30 the insulator may be peripherally grooved, and is also internally threaded as indicated at 33, the grooves being adapted to cooperate with the radial apertures 34 in the shell 11 to establish a path for the circulation of a cooling current of air, and the threads 33 being adapted to cooperate with corresponding threads on a metallic sleeve 35 of copper or other material having good heat conducting qualities, whereby a substantial amount of heat may be taken from the electrode 7 and spindle 14 and transferred through the insulator, to be dissipated along the surfaces of the grooves and through outlets 34. Heat not dissipated in this fashion may be transferred to the second region of air circulation around the heat radiating jacket 15, the heat flow path including parts 19, 28, 18 and 16.

Thus the spindle extension 19 which is riveted to the spindle, serves a double purpose: first, it keeps the spring 36 in place, and secondly, it tends to transfer a large measure of excess heat to the copper ferrule 28, for ultimate radiation by way of jacket 15.

In assembling the plug elements the first step is to braze or otherwise permanently weld the electrode spindle 14 within the metallic sleeve 35, and the second step is to apply a suitable cement to the threaded surfaces 33, so that upon threading the spindle carrying sleeve into the porcelain core 20 to the desired distance, the spindle will become securely bonded to the core 20 by virtue of the cement confined between the registering surfaces of the sleeve 35 and the bore of the core 20. This cementing step, in conjunction with the gasket 31, renders the plug air and gas tight.

55 In forming and installing the type of electrode shown in Figs. 8 to 13, the first step is to secure an H-shaped metallic piece 86 of suitable heat and spark resisting qualities while at the same time a sufficiently good conductor. Such a piece is indicated in Fig. 9. This piece is then subjected to a bending operation to bring it into substantially the form indicated in Fig. 10. Next the parallel sides 87 and 88 are turned into semi-circular arcs which preferably do not quite join (as indicated in Figs. 11 and 12) the cross-connecting portion remaining in the form to which it is initially bent, as shown in Fig. 10. The final step in formation of the electrode is to shape the upper annular surface formed by the semi-circular parts 87 and 88 so that in transverse section it will have the final appearance indicated in Fig. 8. When thus completed the electrode receives a thin dished washer 91 of soft metal such as copper and then a second dished washer 92 of harder material and preferably the same material as the electrode 86 itself. The installation and completion of the electrode assembly is then obtained in the following manner: The shell 36 is placed on a table or work-bench with its lower counter-bore 96 uppermost, a thin cup-shaped liner 97 of soft metal, preferably the same material as that of the piece 91, and centrally aper-

tured to a diameter corresponding to the diameter of the chamber 34, is then inserted in the recessed end 96. The electrode assembly consisting of the parts 86, 91 and 92 is then placed in position within the inverted cup member 97 and the assembly consisting of the parts 36, 91, 92, 91 and 86, is then placed in a hydrogen gas furnace or other suitable heat chamber and subjected to a temperature sufficient to cause a fusion or welding along the surfaces of the elements 97 and 91, with the result that the five elements above enumerated become fused into a permanently welded single unit. This unit is then removed from the furnace, the core assembly, the shield extension assembly, and upper cable assemblies successively attached thereto in the respective manners above indicated. When this complete assembly has been accomplished it will be found that the inner electrode 25 occupies a position approaching that of the transverse portion 86 of the outer electrode and also approaching that of the inner cylindrical edge 99 of the thimble 92, forming an auxiliary spark gap, the clearances therebetween being such that the spark will normally jump from the relatively broad surface of the electrode 25 to the correspondingly broad plane surface of the cross-piece 86 of the ground electrode; but if for any reason this normal path of the spark is obstructed—as for example by the formation of ice particles—the spark can then jump from the cylindrical surface of the electrode 25 to the

above described cylindrical surface 99 of the thimble 92 which may therefore be considered as a part of the completed electrode. In fact, it is, of course, possible to have the elements 92, 91 and 86 originally formed as an integral whole rather than being composed of three subsequently united pieces as shown.

What is claimed is:

1. The method of forming a spark plug electrode which comprises the steps of bending the cross-piece of an H-shaped element at points equally spaced from its center, and adjacent the parallel sides thereof, then curving the sides backwardly toward the center of said H-shaped piece into complementary semi-circular shapes so that the two form an annulus adapted to fit the plug base with the cross-piece joined thereto at diametrically opposite locations. 10

2. The method of forming a spark plug electrode which comprises the steps of bending the cross-piece of an H-shaped element at points equally spaced from its center, and adjacent the parallel sides thereof, then curving the sides backwardly toward the center of said H-shaped piece into complementary semi-circular shapes so that the two form an annulus adapted to fit the plug base with the cross-piece joined thereto at diametrically opposite locations and then applying sufficient heat to the said plug base and annulus to fuse the two into a single unit. 15 20 25 30

EDWARD B. NOWOSIELSKI.
